Patented Aug. 2, 1921.

UNITED STATES PATENT OFFICE.

EMERSON HOWE SMITH, OF PARSONS, KANSAS.

TRAIN-ORDER HOLDER.

1,386,435.

Specification of Letters Patent. Patented Aug. 2, 1921.

Application filed June 24, 1920. Serial No. 391,336.

To all whom it may concern:

Be it known that I, EMERSON Howe SMITH, a citizen of the United States, residing at Parsons, in the county of Labette 5 and State of Kansas, have invented certain new and useful Improvements in Train-Order Holders; and I do declare the following to be a full, clear, and exact description of the invention, such as will enable others 10 skilled in the art to which it appertains to make and use the same.

This invention relates to an improved train order holder for use in holding train orders which are to be delivered to the engineer or fireman of a moving train and one 15 object of the invention is to provide a train order holder so constructed that the framework thereof may be formed from a strip of wood which will be bent to provide a bow 20 and to further so construct the holder that the spring which is positioned between the arms of the bow may serve as means for holding the train order and also as means for holding the arms of the bow in tight 25 frictional engagement with a sleeve positioned about the holder at the point where the arms extend from the handle.

Another object of the invention is to so 30 construct this train order holder that the joint between the handle and the free end of the reduced strip forming the bow will be very strong and not liable to break loose.

Another object of the invention is to so construct this train order holder that the reinforcing sleeve for the joint may be moved 35 longitudinally of the handle and draw the arms of the bow toward each other thus compressing the spring and providing a very tight engagement with the order positioned 40 between the spring and one of the arms of the bow.

Another object of the invention is to provide a train order holder which will be comparatively simple in construction and very 45 efficient in operation.

This invention is illustrated in the accompanying drawings, wherein:—

Figure 1 is a view showing the improved train order holder in elevation with an order 50 connected with the holder,

Fig. 2 is an enlarged fragmentary view of the train order holder principally in elevation and partially in longitudinal section.

Fig. 3 is a transverse sectional view taken 55 along the line 3—3 of Fig. 2, and

Fig. 4 is a fragmentary view showing the

train order holder in elevation with the sleeve removed.

This train order holder is provided with a handle 1 which is preferably formed of wood and will be of sufficient diameter to permit it to be easily grasped. The strip from which the frame, of which the handle forms a portion, is formed, is reduced in thickness as shown in Figs. 2 and 4, thus 60 providing a flexible and resilient strip which can be easily bent to provide the bow 2 through which the engineer will pass his arm as the train passes a station. This bow 2 has its arms 3 and 4 extending in converging relation toward the handle 1 with the free end of the strip engaging the shoulder 5 formed when the strip forming the frame is reduced to provide the bow forming section of the train order holder. A loop 6 which 65 is formed of spring metal such as steel is positioned between the arms of the hoop and has its arms 7 extending between the arms of the hoop and secured by the nail 8 which is driven through the arms of the hoop 70 and clenched as shown in Fig. 2. It will thus be seen that the nail serves to hold the loop 6 in place and also serves to secure the end of the arm 3 in place upon the shoulder 5. 75

In order to reinforce this train order holder at the joint between the end of the arm 3 and the handle, there has been provided a sleeve 9 which is formed of metal and has its upper end portion flared slightly 80 so that it can move into easy engagement with the diverging arms 3 and 4. When this sleeve is put in place, it is moved longitudinally of the handle and as it engages the arms 3 and 4 and is forced upon these arms, 85 it will serve to compress the arms and force them toward each other thus moving them from the position shown in Fig. 4 to the position shown in Fig. 2 and compressing the spring loop. The expansion of the spring 90 loop and the tendency of these arms 3 and 4 to return to the position shown in Fig. 4 will serve to frictionally hold the sleeve in place and prevent this sleeve from accidentally slipping down upon the handle. This 95 pressure will also cause the arms of the loops 6 to have a very tight engagement with the arms 3 and 4 of the hoop and a message 10 which is placed between the loop 6 and one of the arms of the hoop will be very 100 tightly gripped. It will thus be seen that when in use, the message can be inserted be-

tween the loop and one of the arms of the hoop and the sleeve then forced tightly upon the arms of the hoop to bring the hoop and loop into very tight engagement with 5 the message. The station master can then stand upon the platform or near the track and as the train passes the engineer can pass his arm through the hoop and draw the train order carrier into the cab of the engine 10 without danger of the wind caused by the train carrying the message free from the order carrier.

What is claimed is:—

- 15 1. A train order holder having a frame formed from a strip of material reduced to provide a section having flexibility and resiliency, the reduced section being bent to provide a bow having arms converging toward the handle, a loop formed of resilient metal doubled intermediate its length to provide converging arms extending between the converging arms of the bow, a fastener passing through the arms of the bow and loop, and a sleeve positioned about the handle and extending to engage the converging end portions of the bow arms, the sleeve compressing the arms of the bow to compress the loop and being held in place by frictional engagement.
- 20 25 30 2. A train order holder comprising a frame formed from a strip having an enlarged end portion constituting a handle, the strip being bent to provide a bow having

converging arms, a spring loop having converging arms extending between the arms 35 of the bow, a fastener passing through the arms of the bow and loop, and a sleeve slidably mounted upon the handle and converging end portions of the bow arms for reinforcing the arms and forcing the arms to 40 toward each other to provide tight engagement between the arms of the bow and loop.

3. A train order holder having a frame provided with arms extending in converging relation, a spring loop positioned between 45 the arms of the frame and having frictional engagement with the frame, and a reinforcing loop positioned about the converging end portions of the arms, the loop being held in place by frictional engagement with the 50 arms and compressing the arms to provide tight engagement with the spring loop.

4. A train order holder comprising a frame having a bow provided with converging arms of yieldable material, a resilient 55 order engaging element positioned between the arms of the bow and having arms engaging the arms of the bow, and means for moving the arms of the bow toward each other to compress the resilient train order engaging element and provide tight engagement between the train order engaging element and the arms of the bow.

In testimony whereof I have hereunto set my hand.

EMERSON HOWE SMITH.
